RECLINING ARTICLE OF FURNITURE

Anton Lorenz, Buffalo, N. Y.

Application May 1, 1945, Serial No. 591,258

6 Claims. (Cl. 155—106)

1

This is a continuation-in-part of patent application Ser. #552,987 relating to a Reclining article of furniture, filed September 7, 1944.

The present invention relates to furniture, and more particularly to a reclining article of furniture wherein the seat and a downward extension of the back-rest form movable links and a portion of a support forms the stationary link of a polygonal compound linkage.

An object of the invention is to provide a reclining article of furniture of above described type, wherein the movable members of the article of furniture are very well balanced, so that an occupant resting in the article of furniture may bring the movable members of the article of furniture from one position into another position without great effort.

A further object of the invention is to provide a reclining article of furniture of above described type with a leg-rest, which is pivoted to the seat and controlled by a controlling mechanism in such a manner, that the leg-rest may be swung through a relatively large angle during a movement of the members of the article of furniture from their sitting position into their extreme reclined position, so that the leg-rest may be brought into a substantially horizontal position when the members of the article of furniture are in their extreme reclined position.

Another object of the invention is to provide a reclining article of furniture of above described type with or without a leg-rest pivoted to the seat and controlled by a controlling mechanism, wherein the members of the article of furniture may be adjusted by the user of the article of furniture in such a manner, that various changes in the angles between the members of the article of furniture may be obtained during movements of the movable members of the article of furniture from the sitting position into a certain reclined position.

Still another object of the invention is to improve upon reclining articles of furniture as now ordinarily made.

With the above and other objects of the invention in view, the invention consists in the novel construction, arrangement and combination of various devices, elements and parts, as set forth in the claims thereof, certain embodiments of the same being described in the specification and being illustrated in the accompanying drawings forming part of this specification, wherein:

Fig. 1 is a side elevational view of an adjustable reclining arm-chair according to the invention, wherein the guiding link is pivoted to the

lower connecting link of the polygonal linkage, one side frame of the chair being partly broken away so as to show the mechanism of the arm-chair.

Fig. 2 is a sectional view of the locking device of the chair shown in Fig. 1, taken on line 2—2 of Fig. 1, in an enlarged scale.

Fig. 3 is a sectional view taken on line 3—3 of Fig. 2.

Fig. 4 is a side elevational view of a different embodiment of an adjustable reclining arm-chair according to the invention, wherein the guiding link is pivoted to an extension of the lower connecting link of the polygonal linkage, one side frame of the chair being partly broken away for the exposure of the mechanical parts of the chair.

Fig. 5 is a side elevational view of still another embodiment of an adjustable reclining chair according to the invention with a leg-rest pivoted to the front portion of the seat and controlled by a controlling link pivoted to the back-rest, one side frame of the chair being broken away.

Fig. 6 is a side elevational view of a further embodiment of an adjustable reclining arm-chair equipped with means whereby the position of the pivotal connection between two movable members of the chair may be adjusted, and wherein the controlling link of the leg-rest is pivoted to an extension of the back-rest, one side frame being partly broken away.

Fig. 7 is a side elevational view of another embodiment of an adjustable reclining arm-chair according to the invention, wherein the guiding link is pivoted to the front connecting link of the polygonal linkage, one side frame being partly broken away, and

Fig. 8 is a side elevational view of an adjustable reclining chair, wherein the guiding link is pivoted to an extension of the front connecting link, one side frame being broken away.

Referring now to Fig. 1, 10 generally indicates the support of an arm-chair, which may be of any conventional type. According to Fig. 1, the support 10 comprises two side frames 11 and 13 made of tubular material and connected with each other by a base frame 15; the side frames provide the arm-rests of the chair.

12 generally indicates a back-rest, 14 indicates a seat, the rear end of which is pivoted to said back-rest 12 at 16. A pair of connecting links 18 and 20 is arranged on each side of the chair. Said pair of connecting links includes the lower connecting link 18 and the front connecting link 20 pivotally connected with each other at 22,

the effective length of the front connecting link being smaller than that of the lower connecting link. The rear end of each lower connecting link 18 is pivoted below the seat at 23 to a downward extension 24 of the back-rest 12. The upper end of each front connecting link 20 is pivoted to the front portion of the seat 14 at 26. The pivotally interconnected extension 24 of the back-rest 12, seat 14, and pair of connecting links 18 and 20 form a four-sided link-system, which is swingably mounted on lugs 28 of the side frames of the support 10 at the pivot point 16 between the back-rest 12 and the seat 14. A guiding link 30 is arranged on each side of the chair for controlling the movements of the movable members or links 12, 14, 18, 20. One end of each guiding link 30 is pivoted to a connecting element 33 of the side frame at 32 at a point spaced from the pivotal connection 16 between the four-sided link-system 24, 14, 20, 18 and the support 10, the other end of each guiding link 30 is pivoted to an intermediate point of the lower connecting link 18 at the point 34 spaced from the pivotal connection 22 between the two connecting links 18 and 20.

As will be readily understood, the various members of the link-system of the chair may be readily made of such a length relative to each other, that the movable members of the chair are very well balanced and may be easily brought from one position into another. Fig. 1 shows in full lines the movable members of the chair in a sitting position. When the occupant of the chair leans his body against the back-rest 12, he may move the movable members of the chair without great effort from the sitting position into a reclined position as shown in dash and dot lines in Fig. 1.

According to Fig. 1, the chair is provided with a locking device generally indicated by 40, by means of which the movable members of the chair may be held in any desired comfortable position. As shown in said Fig. 1 and in Figs. 2 and 3, said locking device 40 comprises a locking rod 42 pivoted to the seat 14 at 44 and slidably engaged with a clip 46. A supporting element 41 is secured to a connecting member 43 of the side frame 11. A bolt 48 having a head 45 at one of its ends and having a threaded portion 47 at its other end passes through a bore 49 of the supporting element 41, through the bore 51 of a washer 53 interposed between the supporting element 41 and the clip 46, through the bores 55 of the clip 46, and through the bore 57 of a sleeve 59 slidably arranged in a bore 61 of the connecting member 43 and interposed between the clip 46 and a locking knob 50 screwed on the threaded end portion of the bolt 48. A nose 63 arranged on the bolt 48 and engaged with a recess 65 of the supporting element 41 prevents a rotation of the bolt 48 by the locking knob 50. When the locking knob 50 is loosened, the locking rod 42 may freely slide in the clip 46, and, consequently, the movable members of the chair may freely be moved from one position into another one. When the locking knob 50 is tightened, the sleeve 59 is urged against the clip 46, whereby said clip is tightened on the locking rod 42, so that the members of the chair are held in their position.

Furthermore, the locking rod 42 is provided with adjustable limiting means or stops 36 and 38 for limiting the extreme sitting position and the extreme reclined position of the movable members of the chair. As best shown in Fig. 3, said stops 36 and 38 are in the shape of rings

5 mounted on the locking rod 42 provided with a series of threaded bores 67 and 69. Said rings or stops 36 and 38 may be adjusted in various positions by means of screws 71, 73 threaded into one of said bores 67 and 69 respectively. The sitting position of the members of the chair is limited by an engagement of the ring or stop 36 with the clip 46 as shown in Figs. 1 and 3, and the extreme reclined position of the members of the chair is limited by an engagement of the ring or stop 38 with said clip 46.

6 In the embodiment shown in Fig. 1, the foot-rest 52 is mounted on the rear portion of the base frame 15 of the support 10. Such an arrangement of a foot-rest 52 is advisable, if chairs 15 according to the invention are arranged in rows, for example, in an airplane, railroad car, or theater. If desired, the occupant of a chair may place his feet on the foot-rest 52 mounted on the rear portion of the chair in front of him.

20 In the embodiment shown in Fig. 4, 410 generally indicates the support of an arm-chair. Said support comprises two side frames 411, 413, connected with each other by cross bars 417, 436, 438. The rear end of the seat 414 is pivoted to the back-rest 412 at 416. The showing of Fig. 4 is somewhat diagrammatical, the cushions on the back-rest and the seat are omitted. It is self-evident that such cushions may be arranged on the back-rest and the seat, if desired. The back-rest 412 has an extension 424 projecting downwardly from the pivot point 416 between the back-rest 412 and seat 414. Again, the pivotally interconnected extension 424 of the back-rest 412, the seat 414 and the pair of connecting links 418, 420 form a four-sided link-system swingably mounted on the support 410 at 416 for movement about an axis coinciding with the axis of the pivotal connection between the back-rest and the seat. According to Fig. 4, however, an extension 419 projecting beyond the pivotal connection 422 between the two connecting links 418, 420 is rigidly connected with the lower connecting link 418, and one end of the guiding link 430 is pivoted to said extension 419 of the lower connecting link 418 at a point 421 spaced from said pivotal connection 422 between the two connecting links, while the other end of said guiding link is pivoted to a side frame of the support at 432. Furthermore, according to Fig. 4, the effective length of the front connecting link 420 between the pivots 426 and 422 equals the effective length of the lower connecting link 418 between the pivots 422 and 423. Moreover, the chair is provided with a locking device 440 substantially corresponding to the locking device 40 described above in detail in connection with the chair shown in Figs. 1-3; the locking device 440 of the chair shown in Fig. 4 permitting the locking of the movable members 50 of the chair in any desired position, however, is not equipped with limiting means for limiting the sitting position and extreme reclined position of the members of the chair. According to Fig. 4, the extreme sitting position shown in full lines 55 is limited by the cross bar 436, acting as a stop in cooperation with the extension 424 of the back-rest and the extreme reclined position shown in dash and dot lines is limited by the cross bar 438 acting as a stop in cooperation with the back-rest 412. The operation of the chair shown in Fig. 4 corresponds to the operation of the chair shown in Fig. 1.

65 According to Fig. 5, the support 510 is made of a single piece of tubular material, shaped in such a way that it forms the two side frames.

The seat 514 is pivoted to the back-rest 512 at 516. The back-rest has a downward extension 524 arranged in the center of the chair. One end of a single lower connecting link 518 is pivoted to the extension 524 of the back-rest 512 at 523 and the other end of said lower connecting link is pivoted to one end of a single front connecting link 520 at 522. The other end of said front connecting link 520 is pivoted at 526 to a lug 525 arranged on the seat 514 in the center of the chair. Again, the downward extension 524 of the back-rest, the seat 514, and the pair of connecting links 518, 520 form a four-sided link system swingably mounted on the support 510 at 516. One end of a single guiding link 530 is pivoted to an intermediate point 534 of the lower connecting link 518, the other end of said guiding link is swingably mounted on a transverse rod 532 carried by the side frames of the support 510.

According to Fig. 5, the chair is equipped with a leg-rest 558 pivoted to the front end of the seat 514 at 560. On each side of the chair an extension 575 projecting upwardly from the pivotal connection 560 between the leg-rest 558 and the seat 514 is rigidly connected with said leg-rest. On each side of the chair one end of a controlling link 562 is pivoted to said extension 575 of the leg-rest 558 at 564; the other end of said controlling link 562 is pivoted to a lug 571 of the back-rest 512 at 580. The controlling links 562 providing the arm-rests of the chair serve to control the movements of the leg-rest 558.

When the occupant sitting in the chair leans his body against the back-rest, the movable members of the chair may be brought from the sitting position shown in full lines into a reclined position shown in dash and dot lines. During such a change in the position, the movements of the back-rest and the seat are controlled by the links of the polygonal linkage in the same manner as described above in connection with Fig. 1, and the swinging movement of the leg-rest from its rearwardly inclined position into a substantially horizontal position about the pivot 560 is controlled by the controlling link 562. The sitting position is limited by a stop 536 mounted on the support 510 for cooperation with the seat 514, and the extreme reclined position is limited by a stop 538 mounted on the support for cooperation with the back-rest. A locking device 540 of the type described above in connection with the locking device 40 of the chair shown in Fig. 1 may be used for holding the movable members of the chair in any desired position.

In the chair shown in Fig. 6, 610 indicates the support comprising side frames 611, 613 connected with each other by cross bars 617, 636, 638. The rear end of the seat 614 is pivoted to the back-rest 612 at 616. The rear end of the lower connecting link 618 is pivoted to the extension 624 of the back-rest at 623, and the upper end of the front connecting link 620 is pivoted to the front end of the seat 614 at 626. Said pivotal connection 626 connects also the leg-rest 658 with the seat. On each side of the chair one end of a guiding link 630 is pivoted to an intermediate point of the lower connecting link 618 at 634, while the other end of said guiding link 630 is pivoted to a side frame of the support at 632. The four-sided link-system formed by the extension 624 of the back-rest, the pair of connecting links 618, 620, and the seat 614 is swingably mounted on the side frames of the support

610 at 616 at a point spaced from the pivotal connection 632 between the guiding link 630 and the support 610. Thus, the chair comprises a first link-system having three movable links 624, 618, 630 and one stationary link formed by the portion of the support 610 between the pivots 616 and 632 and a second link-system having four movable links 624, 618, 620 and 614. The links 624 and 618 are common to both link-systems, so that said link-systems being superimposed form a polygonal compound linkage. The movements of the leg-rest 658 are controlled by the controlling link 662, one end of which is pivoted to the leg-rest 658 at 664, the other end of which is pivoted to the extension of the back-rest 624 at 680. The sitting position shown in full lines is limited by the cross bar 638 cooperating with the extension 624 of the back-rest, and the extreme reclined position is limited by the cross bar 638 cooperating with the back-rest 612. The movable members of the chair may be held in any desired position by means of the locking device 640 of the type described above.

The chair shown in Fig. 6 has furthermore some additional useful features by the arrangement of means, whereby the position of the pivotal connection between two movable members of the chair may be adjusted. According to Fig. 6 the seat 614, the lower connecting link 618, the extension 624, and the leg-rest 658 are provided with series of holes 666. As will be readily understood, the pins 622, 623, 626, 634, 664, 680 may be inserted by the user of the chair into selected holes of said series of holes 666. Depending on the selection of the holes, the distance between two or more pivotal connections of the movable members may be changed with the result of different relative positions between the movable members of the chair in various reclined positions. For example, if the user of the chair prefers a less inclined position of the seat in the extreme reclined position, than that shown in dash and dot lines in Fig. 6, he may obtain this feature by changing the position of one or more of the pins 622, 623, 626. Furthermore, for a still greater variety of the adjustments, the front connecting link 620 and the guiding link 630 consist of telescopic elements 679, 681, and 668, 670 respectively, which may be held in any adjusted position by a set screw 683 and 672 respectively. Furthermore, if the user of the chair prefers a different position of the leg-rest in the extreme reclined position than that shown in Fig. 6, he may obtain this feature by changing the position of one or more of the pins 664, 680. Moreover, the controlling link 662 consists of two telescopic elements 675, 676, which may be held in any adjusted position relative to each other by a set screw 678. For example, if the length of the telescopic controlling link 662 is adjusted in the manner shown in Fig. 6, the user of the chair may bring the leg-rest 658 and the seat 614 in alignment with each other when the movable members of the chair are held in the sitting position or a reclined position by extending the length of the telescopic controlling link 662. Furthermore, for example, if in the sitting position of the movable members of the chair the length of the telescopic controlling link is adjusted in such a manner, that, in said sitting position the leg-rest is in alignment with the seat, an alignment of the leg-rest with the seat in a reclined position may be obtained by shortening the length of said telescopic controlling link to a certain extent before the movable member of the chair are

brought from the sitting position into the reclined position. Furthermore, the arrangement of a telescopic front connecting link 620 and a telescopic guiding link 630 and the series of holes 666 permits a change of the position of said front connecting link and guiding link relative to each other, so that they may be brought into a cross-wise arrangement, for example corresponding to the cross-wise arrangement shown in Fig. 4.

In the embodiment shown in Fig. 7, 710 generally indicates the support of an arm-chair. Said support comprises two side frames 711 and 713 connected with each other by cross bars 717. The rear end of the seat 714 is pivoted to the back-rest 712 at 716. The back-rest 712 has a downward extension 724. The pivotally interconnected extension 724 of the back-rest, the seat 714, and the pair of connecting links 718, 720 form a four-sided link-system, swingably mounted on the support 710 at 716. In the chair shown in said Fig. 7, one end of the guiding link 730 is pivoted to a side frame of the support at 732 at a point spaced from the pivotal connection 716 between the four-sided link-system and the support, while the other end of said guiding link is pivoted to an intermediate point 754 of the front connecting link 720 at a point spaced from the pivotal connection 722 between the two connecting links 718, 720. The effective length of the front connecting link between the pivots 726 and 722 is larger than the effective length of the lower connecting link 718 between the pivots 722 and 723. The sitting position shown in full lines is limited by a stop 736 mounted on a side frame for cooperation with the extension 724 of the back-rest, and the extreme reclined position shown in dash and dot lines is limited by a stop 738 mounted on a side frame for cooperation with the back-rest. The movable members of the chair may be held in any desired position by means of the locking device 740 of the type described above.

In the chair shown in Fig. 8, again the downward extension 824 of the back-rest 812, the seat 814 and the pair of pivotally interconnected connecting links 818, 820 from a four-sided link-system swingably mounted on the support 810 at 816. According to Fig. 8, however, an extension 827 projecting beyond the pivotal connection 822 between the connecting links 818, 820 is rigidly connected with the front connecting link 820. One end of the guiding link 830 is pivoted to the support 810 at 832, while the other end of said guiding link 830 is pivoted to the extension 827 of the connecting link 820 at a point 829 spaced from the pivotal connection 822 between the two connecting links 818, 820. Thus, the guiding link 830 and the lower connecting link 818 are in a cross-wise arrangement relative to each other. The sitting position shown in full lines is limited by a stop 836 arranged on the support for cooperation with the extension 824 of the back-rest and the extreme reclined position shown in dash and dot lines is limited by a stop 838 arranged on the support for cooperation with the back-rest. The movable members of the chair may be held in any desired position by means of a locking device 840 of the type described above.

I have described preferred embodiments of my invention, but it is understood that this disclosure is for the purpose of illustration, that the invention may also be applied to various other types of reclining articles of furniture, such as garden chairs, chairs for use in railroad cars,

chairs for use in airplanes, desk chairs, etc., that elements shown in one of the Figs. may also be applied to embodiments shown in other Figs., where such elements are not shown, and that various omissions or changes in shape, proportion or arrangement of parts, as well as the substitution of equivalent elements for those, herein shown and described, may be made without departing from the spirit and scope of the invention as set forth in the appended claims. For example, it is mentioned, that the pivotal connection of the four-sided link-system with the support must not necessarily coincide with the pivotal connection between the back-rest and the seat as shown in the drawings; the four-sided link-system could be pivoted to the support at an intermediate point of the back-rest or seat.

What I claim is:

1. A reclining article of furniture, comprising: a back-rest having a downwardly extending extension, a seat, the rear end portion of said seat being pivoted to said back-rest, a front connecting link, a lower connecting link below the plane of the seat, one end of said front connecting link being pivoted to the front portion of said seat, the other end of said front connecting link being pivoted to the front end portion of said lower connecting link, the rear end portion of said lower connecting link being pivoted to said extension of the back-rest, a support, at least one of said two first mentioned members being swingably mounted on said support, a guiding link, one end of said guiding link being pivoted to said support, the other end of said guiding link being pivoted to a connecting link of said two connecting links, a leg-rest swingably mounted on the front portion of said seat, and a controlling mechanism operatively connected with a movable member of the article and said leg-rest for controlling the movements of the latter.

2. A reclining article of furniture, comprising: a back-rest having a downwardly extending extension, a seat, the rear end portion of said seat being pivoted to said back-rest, a front connecting link, a lower connecting link below the plane of the seat, one end of said front connecting link being pivoted to the front portion of said seat, the other end of said front connecting link being pivoted to the front end portion of said lower connecting link, the rear end portion of said lower connecting link being pivoted to said extension of the back-rest, a support, at least one of said two first mentioned members being swingably mounted on said support, a guiding link, one end of said guiding link being pivoted to said support, the other end of said guiding link being pivoted to one of said two connecting links at a point spaced from the pivotal connection between said two connecting links, a leg-rest swingably mounted on the front portion of said seat, and a controlling mechanism operatively connected with a movable member of the article and said leg-rest for controlling the movements of the latter.

3. A reclining article of furniture, comprising: a back-rest having a downwardly extending extension, a seat, the rear end portion of said seat being pivoted to said back-rest, a front connecting link, a lower connecting link below the plane of the seat, one end of said front connecting link being pivoted to the front portion of said seat, the other end of said front connecting link being pivoted to the front end portion of said lower connecting link, the rear end portion of said lower connecting link being pivoted to said extension of the back-rest, a support, at least one of

said two first mentioned members being swingably mounted on said support, a guiding link, one end of said guiding link being pivoted to said support, the other end of said guiding link being pivoted to said lower connecting link at a point spaced from the pivotal connection between said two connecting links, a leg-rest swingably mounted on the front portion of said seat, and a controlling mechanism operatively connected with a movable member of the article and said leg-rest for controlling the movements of the latter.

4. A reclining article of furniture, comprising: a back-rest having a downwardly extending extension, a seat, the rear end portion of said seat being pivoted to said back-rest, a front connecting link, a lower connecting link below the plane of the seat, one end of said front connecting link being pivoted to the front portion of said seat, the other end of said front connecting link being pivoted to the front end portion of said lower connecting link, the rear end portion of said lower connecting link being pivoted to said extension of the back-rest, a support, at least one of said two first mentioned members being swingably mounted on said support, a guiding link, one end of said guiding link being pivoted to said support, the other end of said guiding link being pivoted to one of said two connecting links at a point spaced from the pivotal connection between said two connecting links, a leg-rest swingably mounted on the front portion of said seat, and a controlling mechanism operatively connected with said extension of the back-rest and said leg-rest for controlling the movements of the latter in dependence on the movements of the back-rest.

5. A reclining article of furniture, comprising: a back-rest having a downwardly extending extension, a seat, the rear end portion of said seat being pivoted to said back-rest, a front connecting link, a lower connecting link below the plane of the seat, one end of said front connecting link being pivoted to the front portion of said seat, the other end of said front connecting link being pivoted to the front end portion of said lower connecting link, the rear end portion of said lower connecting link being pivoted to said extension of the back-rest, a support, at least one of said

5 two first mentioned members being swingably mounted on said support, a guiding link, one end of said guiding link being pivoted to said support, the other end of said guiding link being pivoted to one of said two connecting links at a point spaced from the pivotal connection between said two connecting links, a leg-rest swingably mounted on the front portion of said seat, and a controlling link, one end of said controlling link being pivoted to said extension of the back-rest, the other end of said controlling link being pivoted to said leg-rest.

10 6. A reclining article of furniture, comprising: a back-rest having a downwardly extending extension, a seat, the rear end portion of said seat being pivoted to said back-rest, a front connecting link, a lower connecting link below the plane of the seat, one end of said front connecting link being pivoted to the front portion of said seat, the other end of said front connecting link being pivoted to the front end portion of said lower connecting link, the rear end portion of said lower connecting link being pivoted to said extension of the back-rest, a support, at least one of said 15 two first mentioned members being swingably mounted on said support, a guiding link, one end of said guiding link being pivoted to said support, the other end of said guiding link being pivoted to one of said two connecting links at a point spaced from the pivotal connection between said two connecting links, and means whereby the position of the pivotal connection between two movable links of the link-system of the article may be adjusted.

35 ANTON LORENZ.
